EDGE BEVELING TOOL

Martin Leibow, 7007 Mason Dells,
Dallas, Tex. 75230

Filed June 24, 1966, Ser. No. 2,803

Term of patent 14 years

(Cl. D54—13)

Fig. 1

Fig. 2

Fig. 3

Fig. 4

FIGURE 1 is a perspective view of an edge beveling tool showing my new design.

FIGURE 2 is a top plan view of an edge beveling tool showing my new design.

FIGURE 3 is a side elevational view of an edge beveling tool showing my new design.

FIGURE 4 is a bottom plan view of an edge beveling tool showing my new design.

The side not shown is substantially like the side disclosed.

I claim:

The ornamental design for an edge beveling tool, as shown and described.
